UNITED STATES PATENT OFFICE.

WILLIAM BRANDON SATTERLEE, OF TACOMA, WASHINGTON.

MOLD.

1,145,270.

Specification of Letters Patent.

Patented July 6, 1915.

Application filed September 3, 1913. Serial No. 788,014.

To all whom it may concern:

Be it known that I, WILLIAM B. SATTERLEE, a citizen of the United States, residing at Tacoma, in the county of Pierce and State 5 of Washington, have invented new and useful Improvements in Molds, of which the following is a specification.

The invention relates generally to an improvement in molds for line casting machines, and particularly to a mold wherein means are provided for the convenient and speedy adjustment thereof for casting different lengths and thicknesses of slug.

In adjusting the type of mold usually employed in line casting machines to vary the length or thickness of the slug molded, it is necessary for the operator to first unlock the vise, lower the vise to expose the wheel, disengage the mold wheel, revolve the wheel to bring the mold into position for adjustment, remove the cap from the mold to expose the liners, and replace said liners with proper liners to adjust the molding space as required.

It is the object of the present invention to obviate this somewhat lengthy operation by the provision of a mold which may be simply and easily adjustable in a single operation, and in which liners are wholly dispensed with, whereby my improvement is designed not only to effect a saving of time and labor, but also saving the expense in the cost of the liners.

The invention in its preferred form of details will be described in the following specification, reference being had particularly to the accompanying drawings, in which:—

Figure 1 is a view in elevation of the improved mold, the protecting cover being removed to show the means for adjusting the thickness of the molding space. Fig. 2 is a transverse section through the same on the line 2—2 of Fig. 1, one of the slug measure adjusting elements being shown in inoperative or open position. Fig. 3 is a similar view with the elements shown in operative or closed position. Fig. 4 is a section on the line 4—4 of Fig. 1. Fig. 5 is an elevation illustrating the bottom of the mold and showing the relative position of the vise thereto. Fig. 6 is a bottom view of the vise. Fig. 7 is a section on the line 7—7 of Fig. 5.

Referring particularly to Figs. 1 to 4 of the accompanying drawings, wherein is illustrated the improved mold, it will be seen

that said mold comprises a main block 1 adapted to be secured to the mold wheel 2 in the usual manner as by screws 3, and a cap plate 4. The space between the cap plate and the upper surface of the block 1 or more particularly the upper surface of the element to be later described, constitutes a molding space, and in the adjustment of the transverse dimension and length of this space provision is made for varying the measure and thickness of the slug. The lower block is longitudinally slotted throughout its length as at 5, the rear or inner wall 6 of said block being of materially less thickness than the forward or outer wall 7. In the space thus provided at the respective ends of the block, are mounted what may be termed end molding members 8, preferably in the form of comparatively elongated sections, the upper surface of which remains at all times in contact with the lower surface of the cap 4 through the medium of springs 9. The end molding members form permanent molding ends for the molding space, and the distance between the respective inner edges of these members provides a maximum length slug for which the particular mold is designed. Intermediate the members 8 there is slidably arranged in the channel 5 a series of mold limiting sections 10 each of which is normally spring pressed toward the cap through the medium of springs 11 arranged in the channel beneath said members. The members 10 are of any appropriate thickness, as for example, there may be one provided of four picas in thickness, and the remaining members each six points in thickness, though this detail both as to relative size of the members and their number may be carried to any extent and any degree desired, as may be found necessary.

As previously described, the space between the adjacent surfaces of the members 10 and the cap 4 form the molding space, and that therefore the movement of any of said members 10 to close the space will of course vary the length of such space, and hence the length of the slug. Each member is normally held in operative or open position by a trigger 12 pivotally connected thereto and having an operative end depending below the lower end of the forward wall 7 of the block 1, each trigger having a projection 13 designed to engage in a notch 14.

on the relatively inner surface of said wall 7, to hold the member in such operative or open position, it being apparent that upon tripping the trigger springs 11 will operate to force the particular member 10 released into contact with the cap 4 to close the molding space.

To vary the transverse dimension of the molding space and therefore adjust the thickness of the slug, secured upon the block 1 is a housing 15 overlying the cap plate and preferably of outwardly curved form, as shown. Arranged within the space between the inner upper surface of the housing and the cap 4 is an adjusting block 16 having spaced similarly inclined surfaces 17 with which screws 18 adjustably mounted in the casing 15 are adapted to coöperate. The bottom surface of the adjusting block 16 overlies the cap 4 and bears thereon through the medium of ball bearings 19. A lever 20 hereinafter termed the adjusting lever, is pivotally connected to the cap 4 and extends through the casing, said lever being also movably connected to the adjusting block 16 through the medium of a pin and slot connection 21. That end of the lever which projects through the casing is formed within the casing with a spring pressed dog 22 adapted to engage in one of a series of teeth 23 on a notched section formed on the casing. The projecting end of the lever 20 is formed to receive what may be termed the wrench 24, the socketed end of which is adapted to fit over the upper end of the lever and when moved downwardly thereon to depress the dog to withdraw the same from coöperation with the teeth of the segment, whereby the lever may be swung in either direction through the proper operation of the wrench. A locking pin 25 is rotatably mounted in the member 8 and passes through the cap 4 and through the casing 15, that portion of the pin passing through the cap 4 being eccentric so that when turned to one position the cap may be freely moved vertically and when turned to another position the cap will be frictionally engaged and held in its adjusted position.

With the construction described for adjusting the thickness of the slug, it is obvious that upon releasing the lever from the segment, it may be swung in either direction to correspondingly move the adjusting block 16 with the effect to elevate or depress the cap 4 and thereby vary the thickness of the molding space, the withdrawal of the wrench from the lever permitting the dog 22 to engage the immediately adjacent teeth of the segments, thereby locking the cap 4 in the then adjusted position. It is therefore obvious that without the disconnection or separation of any part the mold may be conveniently and readily adjusted to vary the thickness of the slug.

For manually controlling the release of the sections 10, whereby the measure of the slug is adjusted, I provide the usual operating device illustrated more particularly in Figs. 5, 6 and 7, and connected to the vise frame 26. The operating device comprises a block 27 secured to the vise frame 26 by a plate 28, and in this frame is slidably mounted a series of push rods 29, corresponding in number to the number of members 10 of the mold and so spaced with relation to each other that when in proper position they will each rest opposite the projecting ends of one of the triggers 12. The end of each push rod remote from the section 10 is formed with a laterally extending notch 30, so that a channel is formed lengthwise the push block. An operating bar 31 is slidably mounted on the outer surface of the block through the medium of slots 32 formed in that portion of the plate 33 overlying the bar which slots coöperate with pins 34 taking into the block 27. The operating bar is formed in that portion in transverse alignment with the channel 30, with a similar channel 35, and is further provided with a lateral finger piece 36. A slug measure controlling slide 37 is arranged to slidably engage the channels 35 and 30, being provided with a handle 38 whereby it may be moved to any desired position lengthwise the operating bar. A scale 39 is arranged beneath the push rod and accurately indicates the slug measure through appropriate scale marks. In the use of this operating device, assuming the operator to desire to adjust the slug measure to twenty em length, he will, through the medium of the handle 38, adjust the bar 37 until one end thereof registers with the twenty mark on the scale 39. This will cause the bar 37 to coöperate with certain of the push bars. Thereupon the operator pushes inward upon the handle 38 of the bar 31, and through the connection between this bar and the particular push bars, through the measuring bar 37, said particular push bars are moved outwardly and engage the particular triggers 12, releasing these triggers so that the springs 11 may force the members 10 upwardly until they are in contact with the cap and thus close the mold space. Of course only those parts corresponding to the push bars operated will be released, and as any desired number of push bars may be selected for operation, it is obvious that the measure or length of the slug molding space can be readily adjusted without the use of liners and without removing any portion or part of the device to permit such adjustment.

What is claimed is:—

1. A mold for type casting machines comprising a block, a series of elements carried by the block to vary the length of the molding space, independent means coöperating

with each element for normally holding said element in inoperative position and independent means coöperating with each element for automatically actuating said element upon release of its particular holding means.

2. A mold for type casting machines comprising a block, a series of elements carried by the block to vary the length of the molding space, a trigger carried by each element for normally holding said element in inoperative position, and a spring coöperating with each element for automatically actuating said element upon release movement of the trigger.

3. A mold for line casting machines including a main block having an overlying casing, a cap movable in the casing and forming with the main block a molding space, an adjusting block mounted in the casing and overlying and bearing on the cap, said block being formed with spaced similarly inclined wedging surfaces, screws adjustably mounted in the casing and bearing respectively on said wedging surface, and means carried by the cap and connected to the block for operating the latter longitudinally of the cap to move the cap toward the main block.

4. A mold for type casting machines comprising a block, a series of elements carried by the block to vary the length of the molding space, a trigger carried by each element for normally holding said element in inoperative position, and a spring coöperating with each element for automatically actuating said element upon release movement of the trigger, in combination with an operating device including a series of elements

designed in actuating to coöperate with the 40 respective triggers.

5. A mold for line casting machines including a molding block formed to provide a molding space, a series of measure adjusting elements mounted in the block and movable across the molding space to carry the length thereof, means for moving said elements across the molding space, means for holding the elements against operation by such moving means, in combination with a 45 device to simultaneously operate a selected number of such holding means, said operating device comprising a series of push rods each formed with a recess, an operating bar arranged for manual movement and formed 50 with a recess, and a connecting bar slidable in the recess of the push rod and in said recess in the bar, whereby the operating bar in movement will actuate all of the push bars having their recesses engaged by the connecting bar.

6. In combination with a line casting machine mold including a series of movable elements adapted to vary the length of the molding spaces and means for locking each 55 of said elements independently against operation, an operating device including a plurality of push rods, one for each element locking means, means for selecting a series of such push rods for actuation, and means for simultaneously actuating such selected 60 push rods.

In testimony whereof I affix my signature in presence of two witnesses.
